UNITED STATES PATENT OFFICE.

GUY P. THURBER, OF PITTSBURGH, PENNSYLVANIA.

ELECTRICALLY PROPELLED AND CONTROLLED RAILWAY SYSTEM.

1,195,534.

Specification of Letters Patent. Patented Aug. 22, 1916.

Application filed October 24, 1912. Serial No. 727,502.

To all whom it may concern:

Be it known that I, GUY P. THURBER, a citizen of the United States, and a resident of Pittsburgh, in the county of Allegheny and State of Pennsylvania, have invented 5 certain new and useful Improvements in Electrically Propelled and Controlled Railway Systems, of which the following is a specification.

10 The present invention relates to an electrically propelled and controlled railway system, and its object is to exercise a control over the train by means of an electric train controlling circuit, in such a manner 15 that the current of the propulsion and train controlling circuits will not interfere with each other.

By the above system, the train is propelled and controlled absolutely by normally closed 20 electric circuits and any failure of these circuits will operate to control the train. The amount of control exercised by the train controlling circuit may vary, but preferably any abnormal condition will take the control 25 absolutely out of the hands of the engineer and will cause the train to be stopped automatically.

Other features of the invention will appear as the specification proceeds.

30 In the accompanying drawings the invention is embodied in several concrete and preferred forms, but changes and modifications may be made therein without departing from the spirit and scope of the invention.

35 In the drawings: Figure 1 is a diagrammatic view of an electrically propelled and controlled railway system, embodying the invention. Fig. 2 is a diagrammatic view showing a more complete form of train 40 controlling circuit. Fig. 3 is a vertical sectional view of the cut-out valve. Figs. 4 and 5 are horizontal sections on lines 4-4 and 5-5 respectively of Fig. 3. Fig. 6 is a detail view partly in section of parts of the

45 air brake system and train controlling circuit, showing the relation between the two, with the parts in the normal running position. Fig. 7 is a view similar to Fig. 6 showing the parts in the position they occupy 50 when the automatic control is cut out. Fig. 8 is a detail view of the cut-out valve as shown in Figs. 6 and 7 with the parts in the restoring position. Fig. 9 is a detail view of the connection between cut-out valve 43

55 and the air brake system. Fig. 10 is a diagram of the track wiring that may be

utilized in connection with the invention. Figs. 11, 12 and 13 are diagrammatic views of the trucks 14 and 16 and their position at various stages in crossing the insulated section.

Similar characters of reference indicate corresponding parts in the several views.

The general features of the invention can best be understood by considering the diagram Fig. 1.

The two trucks 14 and 16 there represented indicate a train 1 which may consist of one or more cars. 2 is a conductor along the line of way carrying the propulsion current. This propulsion current may be of any character, such as a single phase alternating current, but in the form here shown it is intended to carry a direct current received from the source 100. The rails 63 and 64 of the traffic track form the return path for the propulsion current and one of the poles of the generator 100 is suitably connected to the said rails.

The propelling mechanism on the train 80 may receive this current in any suitable manner. For instance the conductor 2 may be a third rail and the train may have a contact shoe in engagement therewith in a well known manner, but in the preferred embodiment of the invention the conductor 2 is a trolley wire supplying the trolley 3 on the train with propulsion current.

85 The propulsion current may be utilized in any suitable manner to propel the car. 90 In the form here shown a motor 4 is connected to each axle and in circuit with the trolley 3 by means of the conductor 5 and the controller 6 and leads therefrom to be more fully hereinafter described.

95 Carried on the train is a train controlling or indication circuit normally charged from a suitable source of supply furnishing a current having a different characteristic from that of the propulsion current. Thus 100 if the propulsion current is a single phase current of a certain frequency, the current of the train circuit may be a single phase current of a different frequency, or it may be a multi-phase current &c. In the present instance where the propulsion current is a direct current, the train controlling circuit is charged with a single phase current of any suitable frequency.

110 The source of supply for the train controlling circuit may be of any suitable nature. Preferably a part of the propulsion

current may be utilized after modifying it to give it a different characteristic.

In the form shown a rotary transformer 7 is carried by the train and is supplied with current from the propulsion circuit by means of the conductor 8. Another conductor 9 leads from the rotary transformer 7 to one of the trucks 14 where it is grounded. The modified current produced by the transformer 7 is then taken from the collector rings 10 and utilized in the manner herein-after described.

The train controlling circuit may of course take many forms, and may comprehend a plurality of subsidiary circuits or a single circuit, and may be used for the purpose of indication or train control or both.

In one of the preferred forms shown in Fig. 1, the rotary transformer 7 feeds the primary 11 of a transformer. The secondary 12 of this same transformer is connected by means of a conductor 13 to one set of trucks 14 of the train, the current from thence passes through the traffic tracks 63 and 64 to another set of trucks 16 insulated at 15 from the body of the train. From the truck 16 extends a conductor 17 to the armature 18, and from the latter a conductor 19 to the circuit breaker 20 responsive to the train controlling circuit and normally energized thereby. From thence the path is through conductor 21 back to the secondary 12. The circuit just described may be termed the main circuit and its function, in this instance, is to control the circuit breaker 20, which latter then, in turn, controls a subsidiary circuit presently to be described. When the circuit breaker 20 is deenergized it also breaks its own circuit by the dropping of armature 18.

32 is a circuit breaker controlling the armature 32^a in the propulson circuit conductor 5, and normally held energized by means of current received from the transformer 7 by means of conductor 26, armature 27, conductor 28, conductor 33, conductor 34, conductor 29, armature 30 and conductor 31.

The armatures 27 and 30, as shown, are under the control of the circuit breaker 20, and, when the latter is deenergized by the rupture of the main circuit, the armatures 27 and 30 drop thereby breaking the subsidiary circuit just described and deenergizing the circuit breaker 32. This causes the armature 32^a to drop and in this way the supply of propulsion current to the controller 6 will be cut off, but it will be observed that the supply of current to the rotary transformer 7 continues uninterruptedly.

Any suitable means may be provided for restoring the broken circuits, but in the present instance there is provided a conductor 58 connected to the conductor 19 at one end and terminating at its other end in the

contact 57. Leading from the conductor 13 is a conductor 59 terminating in a circuit closer 56 normally held out of engagement with the contact 57 by means of the spring 56^a. When the circuit closer 56 is brought into engagement with the contact 57 the following restoring circuit is established. From the secondary 12 of the transformer, to conductor 13, to conductor 59, to circuit closer 56, to contact 57, to conductor 58, to conductor 19, to circuit breaker 20, to conductor 21, back to secondary 12. The establishing of this circuit will energize the circuit breaker 20, and will cause it to pick up armatures 18, 27 and 30 thereby reestablishing its own circuit and the circuit through the circuit breaker 32, unless there is a break-down in the system or unless other conditions prevent it, in which case the circuits will be broken again.

In order to control the train controlling circuit insulated sections 142 are provided in the traffic tracks 63 and 64 dividing said tracks into block sections. By this means the train controlling circuit, which is normally completed through the traffic tracks, may be ruptured, and the train controlled in each block.

In order to permit the free passage of the train propulsion current, and to permit the completion of the train controlling circuit when the train passes over the insulated section 142 when there is no other train within the danger zone, paths are provided around the insulated section for the propulsion and controlling circuits. These paths should be of such a nature that the controlling circuit may be ruptured without breaking the path for the propulsion current. And the path for the propulsion current should be of such a nature that, while it will permit the passage of the propulsion current it will prevent the completion of the train controlling circuit. Accordingly there is provided a jumper circuit 101 around the insulation 65, through which the train controlling circuit will be normally completed, and an impedance 66 bridges the insulated section 142, which impedance constitutes a path for the propulsion current, but will not permit the passage through it of the train controlling current. The nature of this impedance 66 will of course vary to suit different currents employed. If the propulsion current and the train controlling current were both alternating or pulsating currents, they would vary in their characteristics by having a different frequency or otherwise, and the impedance 66 would be constructed accordingly to permit current of one characteristic to pass and to prevent currents having a different characteristic from passing. In the present instance we have stated that the propulsion current is a direct current, and that the current of the train controlling

circuit is an alternating current, so, in the present case, the impedance 66 will be so constructed that the direct propulsion current will pass freely through the same, but 5 the alternating current from the secondary

12 will not pass therethrough, and the train controlling circuit will therefore be broken, unless the jumper circuit 101 is complete.

Any suitable means may be employed for 10 breaking the jumper circuit 101. In the present instance, a circuit breaker 102 controls the armature 103 interposed in the conductor 101. So long as the circuit breaker 102 is energized, the armature 103 15 will maintain the jumper circuit 101 closed, and will permit the train controlling circuit being completed.

The propulsion current is led from the controller 6 through conductors 104 to the 20 field windings 105 which are in series with the armatures of the motors 4. The armatures of the motors 4 on the truck 14 are grounded on that truck by means of the conductors 106, 107, while the armatures of the 25 motors 4 on the insulated truck 16 are grounded either through the body of the train 1 or on the uninsulated truck 14 by means of conductors 109, 110, and 108 and impedance 111. It will be noted that the 30 motors 4 on the truck 16 are below the insulated portion 15 of that truck, and in order to prevent the train controlling circuit from passing around the insulation 15, it is necessary to use an impedance 111. 35 This impedance 111 connects two trucks spaced apart in the direction of the length of the train, and is connected to the insulated truck 16 at a point below the insulation 15.

By this means the propulsion current 40 turns freely to ground from the motors 4 on the insulated truck 16, while completion of the train controlling circuit through this ground circuit is prevented. It will be obvious that, if the train controlling circuit 45 should be able to pass around the insulation 15, or across from one truck to another, without going through the track, there would be no way of rupturing said train controlling circuit when a broken jumper 50 circuit is reached. The insulation 15 therefore constitutes a means for forcing the train controlling circuit through the traffic track and jumper circuit, and the impedance 111 constitutes a means for grounding the prop- 55

ulsion current on another truck (14) while preventing the completion of the train controlling circuit through the ground conductors for the motors. Again the field 105 and armature windings of the motors 4 form a 60 sufficient impedance to prevent the current of the train controlling circuit from passing up through the conductors 104.

In Figs. 2 to 9 inclusive is shown a more comprehensive form of train controlling circuit. The propulsion circuit and the paths

for the propulsion circuit and train controlling circuit around the insulation in the track having been previously described, it is unnecessary to repeat the same here, except incidentally.

The train 1 has an insulated truck 16 and an uninsulated truck 14 as before, and receives power from the conductor 2, through trolley 3 and conductor 5 to the controller (not shown). The rotary converter 7 receives current from the trolley 3 through conductor 8 and is grounded by means of conductor 9. 7^a is the field winding of the rotary transformer 7. The modified current is taken from the collector rings 10. 70

The rotary transformer 7 feeds the primary 11 of a transformer. The secondary 12 of this same transformer is connected by means of the conductor 13 to one set of trucks 14 of the train, the current from thence passing through the traffic track to another set of trucks 16 insulated from the body of the train. From the trucks 16 extends a conductor 17 to the armature 18, and from the latter a conductor 19 to circuit breaker 20 which is responsive to the current of the train controlling circuit and is normally energized thereby. From thence the path is through conductor 21 to the plate 22 which is insulated both from the trucks 16 85 and the bolster 23, and thence by means of conductor 24 back to the secondary 12. The circuit just described is to control the circuit breaker 20, which latter then, in turn, controls subsidiary circuits presently to be 90 described. The circuit breaker 20 also breaks its own circuit by the dropping of armature 18.

25 is a magnet valve normally energized by the rotary transformer 7 by means of a 105 circuit normally held closed by the circuit breaker 20. This circuit consists of the conductor 26, armature 27, conductor 28, magnet valve 25, conductor 29, armature 30 and conductor 31. It is obvious that, when the 110 circuit breaker 20 is deenergized by the rupture of the main circuit, the armatures 27 and 30 will drop, thereby breaking the subsidiary circuit and deenergizing the magnet valve 25. This magnet valve controls the 115 air brake system in a manner to be presently described.

In multiple with the subsidiary circuit just described is an auxiliary circuit which normally energizes a circuit breaker 32 normally holding the propulsion circuit closed. This auxiliary circuit is formed by the conductors 33 and 34 branching off from the conductors 28 and 29. It follows, from what has been described, that, when the circuit 120 breaker 20 is deenergized and the subsidiary circuit is broken by the dropping of armatures 27 and 30, the circuit breaker 32 will be deenergized, thereby dropping the armature 32^a and the supply of propulsion 125 130

current to the controller will be stopped. It will be observed, however, that the supply of current to the rotary transformer 7 continues uninterruptedly.

5 The train circuits described may control the air brake system in any suitable manner and may be utilized to give either a service application or an emergency application or both. In the preferred embodiment illustrated an emergency application is given.

10 In the present instance the air brake system is controlled as follows: The magnet valve 25 is normally held energized, as previously described, and when energized attracts the armature 35. This latter is connected by means of the stem 36 to two valve members 37 and 38, the former controlling the inlet port 39, and the latter the outlet port 40. The parts are so arranged that 15 when the member 37 is in its closed position, the member 38 is in its open position and vice versa. The inlet port 39 is in communication with some part of the air brake system, such as the emergency pipe 41 by means 20 of the pipe 42, cut out valve 43 and duct 44. Intermediate the valve members 37 and 38 is a port 45, which by means of pipe 46, is in communication with the chamber 47 of the automatic brake valve 48. This latter is 25 provided with a valve member 49 in the casing 50, which valve member 49 controls the exhaust 51 and is normally held closed by the piston 52 connected by means of stem 53 to said member 49. A spring 54 opposes the 30 action of the piston 52. The casing 50 is in communication with the pipe by means of the cut-out valve 43 and pipe 55. Normally the cut-out valve 43 is in the position shown 35 in Fig. 6 and air under pressure is admitted by means of ports 43^a and 43^b both to the magnet valve 25 and to the casing 50. The magnet valve 25 normally holds the member 38 in its closed position and the member 37 in its open position. Air under pressure 40 therefore normally travels through the port 39, past member 37, out through port 45, through pipe 46 and acts against piston 52 to overcome the pressure of the spring 54 and to hold the member 49 in its closed position.

50 Should the magnet valve 25 become de-energized from any cause, such as by the rupture of the train controlling circuit, the spring 35^a will move the stem 36 and the member 37 will be moved to its closed position, shutting off supply from the pipe 41, and the member 38 will be moved to its open position. The air will therefore exhaust from the chamber 47 through pipe 46, past member 38 and out through port 40. The spring 54 will therefore expand and permit air to escape from pipe 41, through duct 44, valve 43, pipe 55, casing 50, past valve 49 and out through exhaust 51, there- 55 by applying the brakes in a well known

manner. By turning the cut-out valve 43 into the position shown in Fig. 8 the supply of air from pipe 41 is shut off to the exhaust 51, and the air is supplied to the magnet valve through port 43^b. If it is desired to 75 cut out the automatic application of the brakes altogether, the valve 43 may be turned into the position shown in Fig. 7 where supply of air is cut off both from the exhaust 51 and magnet valve 25.

75 It is obvious from the foregoing, that turning the valve 43 into the position shown in Fig. 6 will not, of itself, energize the magnet valve 25. Therefore some means must be provided for restoring the broken circuit. 80 These means may take many forms but in the preferred embodiment herein disclosed they are as follows: The valve 43 carries a circuit closer 56 which is normally open but is brought into engagement with the contacts 57, when the valve 43 is turned into the position shown in Fig. 8. The contacts 57 are connected by means of the conductor 58 to the circuit breaker 20, and by means of the conductor 59 to the conductor 13. When the circuit closer 56 is therefore brought into engagement with the contacts 57, the following restoring circuit will be established: From the secondary 12 of the transformer, through conductor 13, conductor 59, circuit closer 56 and contacts 57, conductor 58, circuit breaker 20, conductor 21, plate 22, conductor 24, to secondary 12. The establishing of this circuit will energize the circuit breaker 20, and will cause it to pick up the 90 armatures 18, 27 and 30, thereby establishing the circuit through the magnet valve 25, unless there is a break-down in the system or unless track conditions prevent it, in which case the circuits will be broken again. 100

105 The ports 43^a and 43^b and the circuit closer 56 are so positioned circumferentially with respect to each other that, when the circuit closer 56 is brought into engagement with the contacts 57, (Fig. 8) the port 43^b 110 will connect the duct 44 with the pipe 42 and air will therefore be admitted to the chamber 47 of the automatic brake valve 48 by way of the magnet valve 25, which latter is energized by the closing of the restoring circuit to permit this action to take place. This has the effect of closing the valve member 49. It will be observed, however, that when the port 43^b is in the position shown in Fig. 8, the pipe 55 is not in 120 communication with the duct 44, and the exhaust of air will cease. After the magnet valve 25 is reenergized and the valve 49 is closed, the parts will again assume the position shown in Fig. 6 by means presently to 125 be described and air will then again be admitted to the pipe 55 and casing 50 of the automatic brake valve.

130 The cut-out valve 43 is preferably of the following construction: The valve member

43 has a stem 61. Carried by this stem is the circuit closer 56. A spring 62 normally tends to turn said stem 61 so as to move the ports 43^a and 43^b into the position shown in Fig. 6. 112 indicates a segment carried by the stem 61, said segment having the segmental slot 113 provided at one end with a narrow neck portion 114 and a locking aperture 115. 116 is a plunger of a diameter equal to the width of the slot 113 and equal to the diameter of the locking aperture 115. This plunger 116 has a stem 117 of a diameter equal to the width of the neck portion 114. 118 is a spring normally tending to hold the plunger 116 in its uppermost position and in the plane of the slot 113. When the valve member 43 is turned to restore the circuit through the magnet valve 25 (which may be done by means of a key or wrench) fitting over the squared end 119 of the stem 61, the movement will continue until the shoulders 120 of the segment 112 at the neck portion 114 come in contact with the plunger 116. This will bring the ports into the position shown in Fig. 8. When the key is removed from the squared end 119 the spring 62 will snap the ports back into the position shown in Fig. 6. Should it be desired to cut out the automatic control of the train, the plunger 116 is depressed until the stem 117 is in the plane of the slot 113, when the valve 43 may be turned until the stem 117 enters the locking aperture 115. By releasing pressure upon the plunger 116, the spring 118 will bring said plunger into the plane of the locking aperture 115, and the spring 62 can no longer return the ports to their original position. When the valve 43 is thus locked in the locking aperture 115, the ports 43^a and 43^b will occupy the position shown in Fig. 7, whereby air will not flow either into the pipe 42 or pipe 55. In addition to this, the circuit closer 56 is out of engagement with the contacts 57. When the valve 43 is therefore turned part way, the restoring circuit is completed through the magnet valve 25 and air is admitted to the said magnet valve, and thence to the chamber 47 of the automatic brake valve 48, and when the valve 43 is turned another distance the restoring circuit is no longer completed through the magnet valve 25 and air is cut off both from the chamber 47 and casing 50 of the automatic brake valve. The train will then be under the control of the engineer's brake valve (not shown) in the usual manner.

The wires 58 and 59 for the contacts 57 may conveniently be carried into the casing of the valve 43 through conduits 200.

If the insulation between the plate 22 and the bolster 23 should break down, the following circuit would be established: From secondary 12 to conductor 13, to the top plate of train 1 connecting the trucks 14 and

16, to plate 22 to conductor 24, back to secondary 12.

If the insulation between plate 22 and truck 16 should break down, the following circuit would be established: From secondary 12 to conductor 13, to truck 14, to truck 16, to plate 22, to conductor 24, back to secondary 12. 70

It will be observed that in either case the circuit breaker 20 would become deenergized, and this, occurring between block stations would localize the trouble to the truck 16, and the defect in the system could be readily found. 75

The foregoing describes a preferred arrangement of the train circuit part of the invention. We shall now give a description of the track circuit part of the invention. 80

In Fig. 10 is shown an arrangement of circuits to be utilized in connection with the track construction. The rails 63 and 64 are sectionalized by insulation 65, and 140. These insulations 65 and 140 form main blocks 141 and local blocks 142 as shown. 85 90 The main blocks 141 are provided with track circuits fed from the secondary 125 by means of conductors 126 and 127. The track relay 129 is connected to the track by means of conductors 131 and 132. The local blocks 142 are not charged with any current. 95

66 is an impedance forming a path around the insulations 65 and 140 for the propulsion current. A path is likewise provided around the insulation 65 for the completion of the train controlling circuit consisting in this instance of conductors 142', 143 and armature 144. While the jumper circuit only spans the insulation 65, it is in effect also a path around the insulation 140 because one rail (63) of the local block 142 is shorter than the distance between the two trucks 14 and 16, while the other rail (64) of the local block 142 is longer than the distance between said trucks, and the length of one truck as 14 is less than the short rail (63) of the local block 142, as shown in the diagram Fig. 10, so that as long as the jumper circuit is not ruptured, the train controlling circuit will be completed when the train passes through the local block, and when the jumper circuit is broken the train circuit will be ruptured. 100 115

The track relay 129, as here shown, controls the armature 144' in the line circuit 145 leading to the relay 93 one block station in rear, and this relay controls the jumper circuit at that block station. The relay 93 is normally energized by the secondary 146, and both secondaries 125 and 146 are fed by the primary 147. 120

What is claimed is:

1. An electrically propelled and controlled railway system comprising: a propulsion circuit passing through the train and com- 125 130

- pleted through the traffic track, a normally closed train circuit having a current of a different characteristic from that of the propulsion circuit and normally completed
- 5 through the traffic track, a traffic track divided by insulation, paths around the insulation for the propulsion and train circuits to permit the free passage of the propulsion current and to permit the completion of the
- 10 train circuit when the train passes over the insulation, and means for rupturing the path for the train circuit around the insulation
- 15 2. An electrically propelled and controlled railway system comprising: a propulsion circuit passing through the train and completed through the traffic track, a normally closed train circuit having a current of a different characteristic from that of the
- 20 propulsion circuit and normally completed through the traffic track, a traffic track divided by insulation, a path around the insulation to permit the completion of the train circuit when the train passes over the
- 25 insulation, a path around the insulation to permit the free passage of the propulsion current and having an impedance to resist the completion of the train circuit, and means for rupturing the path for the train
- 30 circuit around the insulation.
3. An electrically propelled and controlled railway system comprising: a propulsion circuit passing through the train and completed through the traffic track, a normally closed train circuit having a current of a different characteristic from that of the propulsion circuit and normally completed through the traffic track, a traffic track divided by insulation, paths around the insulation to permit the completion of the train circuit when the train passes over the insulation and to permit the passage of the propulsion current, an impedance in one of said paths which permits the passage of current having one characteristic and prevents the passage of current having a different characteristic, and means for rupturing the path for the train circuit around the insulation.
4. An electrically propelled and controlled railway system comprising: a propulsion circuit passing through the train and completed through the traffic track, a normally closed train circuit having a current of a different characteristic from that of the propulsion circuit and normally completed through the traffic track, a traffic track divided by insulation, paths around the insulation for the propulsion and train circuits to permit the free passage of the propulsion current and to permit the completion of the train circuit when the train passes over the insulation, and means for preventing the completion of the train circuit through the path for the train circuit around the insulation.

5. An electrically propelled and controlled railway system comprising: a train having two trucks insulated from each other, propulsion motors on the trucks, a propulsion circuit for said motors adapted to be completed through the traffic track, a normally closed train circuit having a current of a different characteristic from that of the propulsion current and normally completed through the traffic tracks, a traffic track divided by insulation, a path around the track insulation for the train circuit, another path around the track insulation for the propulsion circuit, having an impedance to resist the passage of the train circuit current therethrough, a path in the propulsion circuit for the propulsion current extending around the insulation which separates the two trucks from each other, and an impedance in said last-mentioned path adapted to resist the passage of the train circuit current therethrough.

6. An electrically propelled and controlled railway system comprising: a train, a propulsion circuit passing through the train and completed through the traffic track, a normally closed train circuit having a current of a different characteristic from that of the propulsion circuit and normally completed through the traffic track, a traffic track divided by insulation, an insulated and an uninsulated truck on the train, a motor in said propulsion circuit on the insulated truck, paths around the truck insulation and around the track insulation for the propulsion current, each containing an impedance to resist the flow of the current of the train circuit, and a path for the train circuit around the track insulation.

7. An electrically propelled and controlled railway system comprising, a train having two trucks insulated from each other, propulsion motors on the trucks, a propulsion circuit for said motors adapted to be completed through the traffic track, a normally closed train circuit having a current of a different characteristic from that of the propulsion circuit, said train circuit being led to the two trucks so as to be normally completed through the traffic track, a traffic track divided by insulation, a path around the track insulation for the train circuit, another path around the track insulation for the propulsion circuit, means in said second path for resisting passage of the train circuit current therethrough, a path in the propulsion circuit for the propulsion current from the motors on the trucks to the traffic track, extending around the insulation separating the two trucks from each other, and means in the said last-mentioned path adapted to resist passage of the train circuit current therethrough.

8. An electrically propelled and controlled railway system comprising, a train having

- two trucks insulated from each other, propulsion motors on the trucks, a propulsion circuit for said motors adapted to be completed through the traffic track, a normally closed train circuit having a current of a different characteristic from that of the propulsion current, said train circuit being led to the two trucks so as to be normally completed through the traffic track, a traffic track divided by insulation, a path around the track insulation for the train circuit, another path around the track insulation for the propulsion circuit, means in the said second path for resisting passage of the train circuit current therethrough, a path in the propulsion circuit for the propulsion current from the motors on the trucks to the traffic track, extending around the insulation separating the two trucks from each other, means in the said last mentioned path 20 adapted to resist passage of the train circuit current therethrough, and means for preventing completion of the train circuit through the path for the train circuit around the track insulation. 25
- Signed at Pittsburgh, in the county of Allegheny and State of Pennsylvania, this 4th day of October, A. D. 1912.
